COVER FOR A BED HEADBOARD OR SIMILAR ARTICLE

Eloise Maxwell Leigh, 409 Mead St. SE.,
Atlanta, Ga. 30315

Filed Dec. 14, 1970, Ser. No. 26,487

Term of patent 14 years

Int. Cl. D6—01

U.S. Cl. D6—198

FIG.1

FIG.2

FIG.4

FIG. 1 is a front, top and right side perspective view of a cover for a bed headboard or similar article, showing my new design;

FIG. 2 is a rear elevational view;

FIG. 3 is a top plan view; and

FIG. 4 is a bottom plan view thereof.

I claim:

The ornamental design for a cover for a bed headboard or similar article, substantially as shown.
